Des. 206,158
Patented Nov. 8, 1966

206,158

CASE FOR AN ELECTRIC METER

George D. Perkins and David E. Workman, both of Pasadena, Calif., assignors to Pendleton Tool Industries, Inc., Los Angeles, Calif., a corporation of Delaware

Filed Sept. 14, 1965, Ser. No. 86,993

Term of patent 14 years

(Cl. D26—1)

FIG. 1 is perspective view of a case for an electric meter, showing our new design;

FIG. 2 is a front elevational view thereof;

FIG. 3 is a side elevational view thereof;

FIG. 4 is a bottom plan view thereof;

FIG. 5 is a top plan view thereof; and

FIG. 6 is a rear elevational view thereof.

The essential features of our design are shown in full lines.

We claim:

The ornamental design for a case for an electric meter, substantially as shown and described.
